UNITED STATES PATENT OFFICE.

EDWIN H. PIERSEN, OF TOPEKA, KANSAS, ASSIGNOR TO THE PIERSEN MANUFACTURING COMPANY, OF TOPEKA, KANSAS, A CORPORATION OF KANSAS.

DIFFERENTIAL ESCAPEMENT.

1,359,465.

Specification of Letters Patent. Patented Nov. 16, 1920.

Application filed October 2, 1919. Serial No. 328,049.

To all whom it may concern:

Be it known that I, EDWIN H. PIERSEN, a citizen of the United States, residing at Topeka, in the county of Shawnee and State 5 of Kansas, Box 413, Topeka, Kansas, have invented certain new and useful Improvements in Differential Escapements; and I do declare the following to be a full, clear, and exact description of the invention, such 10 as will enable others skilled in the art to which it appertains to make and use the same, reference being had to the accompanying drawings, and to the letters and figures of reference marked thereon, which 15 form a part of this specification.

This invention relates to a mechanism for perforating sheets, tapes or ribbons. Generically, the invention contemplates the provision of means for feeding a tape which is 20 to be perforated in predetermined, variable group arrangements, and for controlling the intermittent advance of the tape or sheet acted upon to maintain uniform space relation between the several character groups 25 of apertures.

The invention also contemplates a transmission capable of transmitting power from a driving part to a driven part in varying increments of movement.

30 The invention is particularly adapted for use in connection with a perforator for telegraphic tape, whereby sets of apertures corresponding to dots and dashes of a code are punched in a paper tape to form a record, 35 which may be run to cause actuation of a circuit making and breaking device so as to effect transmission of electrical impulses which are capable of being translated into characters of a code to indicate a message, as 40 shown and described in my Letters-Patent No. 1,289,900, of Dec. 31, 1918, for telegraph transmitter, of which this is a division, filed after grant of the patent.

As some telegraph codes are made up of 45 different arrangements of dots and dashes, the respective characters vary in length and as it is desirable to maintain standard spaces between characters, it is essential that the record tape be advanced different distances

for characters of various lengths in order to 50 avoid interference of the characters and maintain uniform spacing. To this end the mechanism is so arranged that the tape will always travel a uniform distance for a space plus the increment determined by the length 55 of the character.

For a better understanding of the invention and particularly in relation to telegraph transmitters of the type above mentioned, reference may be had to my co-pending application, Serial No. 313,705, and to facilitate the reference thereto, I have applied like reference numerals to parts herein corresponding to like parts in the co-pending application. 65

In the drawings:

Figure I is a perspective view of an escapement embodying my invention, illustrating its use in connection with a perforator of the type forming the subject matter 70 of my co-pending application, Serial No. 328,050, filed concurrently herewith.

Fig. II is a similar view, particularly illustrating the escapement shift.

Fig. III is an elevation of the escapement, 75 showing the parts in inactive position.

Fig. IV is a similar view, showing the perforator in operative position and the escapement released.

Fig. V is an elevation of a gear train for 80 operating the tape advancing rollers corresponding to the gear train in my co-pending application, Serial No. 313,705.

Fig. VI is a detail perspective view of the universal escapement pawl.

Fig. VII is a similar view of the pawl shifting bracket.

Referring more in detail to the drawings:

1 designates a frame containing operative parts of the mechanism and which preferably comprises a base 2, sides 3 and 4 and feet cushions 5 to avoid vibration, it being understood that the cover of the machine is herein omitted for better illustration. 90

The base 2 comprises a slotted rib 9, provided with a pin or rod 9', upon which the digitally operated means shown as key levers 14, that seat in the slots of the rib, are 95

pivoted. The rear ends of the key levers are guided in slots 10 of a similar rib 11 on the base 2. The front ends of the key levers are upturned and provided with buttons 14', each bearing the designation of a character represented by its key lever. Each key lever is provided, at the rear of its mounting, with a spring 15 which yieldingly retains the lever in normal position. When, however, the key button is struck, the rear portion of the lever will be raised to impress its character upon the record tape, the impress preferably being effected by punching the tape, as will presently be described, and as claimed in my application filed concurrently herewith.

On the upper edge of the rear portion of each lever is a tape impressing section comprising a die 17, consisting of teeth of such length and arrangement as to correspond with the dots and dashes of a code character, the longer teeth representing dashes and the shorter teeth dots, and the spacing between the teeth corresponding to the standard spacing between dots and dashes of the character.

There may be as many digitally operated key levers in the machine as there are characters in the code, each lever having its individual character die, the die portions of all of the levers being arranged in transverse alinement to coöperate with a die plate 19 that is supported in the frame and extended transversely over the die portions of the key levers.

The plate 19 contains apertures 20 corresponding in character and alinement to the die portions 17 of the levers, the plate being so arranged that when the levers are inactive, sufficient space is left between the upper edges of the lever dies and the lower surface of the plate to accommodate a tape 22 that serves as a record member when punched by the die parts. The tape, when punched, may pass in operative relation to a circuit making and breaking device (not shown), which may be of the type illustrated in my co-pending application, to effect transmission of the code character impulses in the order in which they occur in the tape.

In order to avoid confusion between characters, the tape is advanced between each key lever operation so that the character indicia in the tape occur in order of their application thereto in longitudinal succession and at spaced intervals. The standard spacing in telegraph operation consists of one unit of space for a dot, two units for a dash, one unit for a space and three units between characters. It is essential, therefore, that this spacing be maintained in mechanical sending and receiving. The spacing of the dots and dashes of each character is effected

by arrangement of the die teeth on the key levers but the spacing between characters must be effected by mechanical operation and it is for this purpose that I have provided the differential feed mechanism included in this application.

In general, this differential feed mechanism comprises a single driving element whereby the tape is forwarded following the operation of any key lever. Means, individual to each key lever, is provided for limiting the advance of the tape a distance proportionate to the length of the character represented by that particular key lever. For example, should the key lever for the letter "I" be operated, the tape forwarding mechanism is released to advance the tape until stopped by the controlling device for the "I" lever. The character "I," which consists of two slots, comprises three spaces which, together with the space interval between characters, requires a tape advance corresponding to six spaces. Should the key lever for the letter "J" be operated, the tape is advanced a distance equal to twelve spaces, this character in itself requiring nine spaces to correspond with the dash dot dash dot of the character and the three space interval between characters.

The preferred form of the tape advancing and differential feed mechanism comprises rollers 29 and 30, between which the tape is run, after passing beneath the die plate 19. The roller 30 turns on a fixed axis journaled in the side members 3 and 4 of the frame, and the roller 29 in sliding boxes 28 in the sides of the frame. The boxes work in slots 27 in the frame sides and are normally tensioned downwardly by springs 31, bearing against the tops of the boxes and the upper edges of the slotted parts. In this way the movable roller is tensioned toward the fixed roller to afford frictional grip on the tape whereby the latter may be advanced when either of the rollers is rotated.

Fixed on the axis of the roller 30 is a gear 110 wheel 98, driven through a train 99, 93, 84 and 83, from a spring motor 78, which may be wound by hand or otherwise when necessary.

The shaft 45 which carries the train gear 115 99 extends transversely through the frame, parallel with and adjacent to the die plate 19 and fixed to said shaft is a ratchet wheel 46. Rotatable on the shaft 45 is a sleeve 47 and fixed to said sleeve adjacent the ratchet wheel 46 is a bell crank lever 49. Fixed to the opposite end of the sleeve is an arm 48 and carried by the arm 48 and the parallel member 50 of the lever 49 is a universal rod 51 which lies back of a series of differential 120 levers or latches 52 presently described.

The lever 49 carries at its rear end a pin 59' which projects along the edge of the

ratchet wheel 46 and carries a pawl 59, having a tooth yieldingly urged toward the wheel by a spring 60 connected therewith and with the lever 49. The end of the pawl 5 opposite the tooth carries a roller 61, which bears against the concave face of an arc-shaped bracket 62 on a bar 63 that lies alongside of the ratchet wheel. The bar 63 contains an oval shaped aperture 64 in which is 10 located a boss 65 that projects inwardly from the frame side member 3 and serves as a mounting for the bar. Bearing against the outer end of the boss 65 and the forward end of the slot 64 is an expansion spring 66 15 which normally, yieldingly urges the bar rearwardly in the machine to permit the spring 60 to retain the pawl 59 in holding engagement with the ratchet wheel and thereby lock the same against further action 20 by the spring motor. The forward end of the bar 63 has an eye 67 with which is connected a link 68 that extends forwardly and is connected with the upstanding arm 69 of a lever 70 that is mounted on the pin 9' in 25 the same manner as the key levers heretofore described.

The lever 70 is located at one side of the machine and similarly mounted at the opposite side of the machine is an idle lever 74, 30 having an upstanding bearing arm 74'. Mounted on the arm 69 of lever 70 and on the arm 74' of lever 74 and extending over the key levers 14 is a torsion rod 72. Connected with the levers 70 and 74 and extending 35 therebeneath, forward of their pivotal mountings, is a universal bar 73, which is engaged by any of the key levers upon operation thereof, to rock the lever arm 69 and move the link 68 and bar 63 forward. Forward movement of the bar 63 effects 40 corresponding movement of the arc-shaped bracket 62. The bracket 62 upon forward movement engages the roller 61 and rocks the pawl 59 out of engagement with the ratchet wheel 46, thereby freeing the arm 45 49 and pawl 59 so that they will be carried upwardly around the ratchet wheel 46 when the lever 52 is released by the key-lever, it being apparent that when the key-lever is 50 depressed, the lever 52 moves the universal bar 51 and consequently the lever 49, a distance determined by the position of screws 58.

Integral with and forming a part of the 55 lever 70 is a detent 70' comprising a tooth 70" at its rear end, which moves up into locking engagement with the ratchet wheel 46 before the pawl 59 has left its locking engagement therewith so that no movement 60 of the ratchet wheel and the tape forwarding parts is permitted merely by operation of a key lever. Operation of the ratchet wheel is effected subsequently to return of the lever, the pawl and the detent to their

normal relation to the ratchet wheel by the 65 differential feed mechanism which I will now describe.

Rotatably mounted on the sleeve 47 directly in rear of each digitally operated key lever 14, is a bell crank lever or latch 52, 70 there being as many bell crank levers as there are key levers in the machine, each of which is a duplicate of the others but all being mounted to have different throws, the distance of travel being controlled by adjustable stops preferably in the form of screws 58, one for each lever 52. The rear edges of all of the latches are in the same vertical plane when the parts are normal, so that the cross rod 51 which is carried by 75 the arms 48 and 50, thus forming part of the pawl lever 49, lies in contact with the rear edges of all of said bell crank levers when the parts are in normal position. Connected with each of the bell crank levers 80 52 and with a pin 55 on a transverse rib 56 that rises from the frame base 2, is a spring 54, which yieldingly urges its lever rearwardly and away from the rear ends of the key levers 14. The influence of the spring 85 90 is resisted by the hooks 18 and 53 on the key levers and bell crank levers respectively, which normally restrain the bell crank levers and hold the same in normal position.

It is apparent that as each bell crank lever is rigid and urged rearwardly by its spring 54 and that as the corresponding key lever is so mounted that upon operation, its rear end will rise away from the hook portion of the bell crank lever, operation of the key lever will release the bell crank lever so that it is drawn rearwardly by its spring 54. Such rearward movement of any bell crank lever imparts rearward and upward movement to the universal rod 51 on the pawl lever 49, so that the pawl lever is rocked a distance proportionate to the rearward movement of the bell crank lever 52. As movement of the bell crank lever 52 is 100 induced by the spring 54, such movement is instantaneous upon release of the bell crank from the key lever. Consequently, movement of the bell crank lever is effected 105 while the arc-shaped bracket 62 is held forward by the depression of the key lever, through the linkage described and while the pawl 59 is out of locking engagement with the ratchet wheel 46. 110

Movement of the lever 49 on its pivot 120 carries the pawl 59 forward along the ratchet wheel, so that after the operation of a bell crank lever 52, the pawl is in position to engage a different ratchet tooth than before its carrying lever was moved by backward movement of the lever 52. As the parts are moved backwardly by a spring 54, having no connection with the key lever,

they are held in such position when the key lever is released, although release of the key lever effects the return of the arc-shaped bracket to normal position. Upon the rearward movement of the bracket, the spring 60 moves the pawl tooth toward the ratchet wheel and effects engagement of the pawl tooth with a ratchet tooth. Release of the key lever also effects return of the detent 70' to its normal position, thereby releasing the ratchet wheel to the force of the spring motor. Immediately upon release of the ratchet wheel by the detent the motor acts to advance the shaft 45 and the tape feeding rollers operated thereby, so that the tape is advanced a distance corresponding to the forward movement of the ratchet wheel and bell crank lever 49. The forward movement of the bell crank lever 49 and its corresponding arm 48 effects forward movement of the universal rod 51. As the bell crank lever 52 is held yieldingly against the rod 51 by its spring 54, the lever is pushed forwardly by the rod 51 until the rod is stopped by the other bell crank levers 52 that have remained in normal position during the operation just described, the active bell crank lever lifting the rear end of the lever 14 upon contact of the beveled ends of the hooks 18 and 53 as the bell crank lever assumes its normal position so that the key lever hook may drop back to its locking relation with the bell crank.

From the foregoing, it is apparent that the forward movement of the ratchet wheel 46, operating shaft 45 and the tape advancing roller 30, corresponds to the rearward movement of the bell crank lever 52 and that by providing means for limiting the several bell crank levers at different points, variation of the advancing travel of the motor operated parts may be effected. The preferred means for providing such difference in movement of the bell cranks 52 consists of set screws 58, which are mounted in the upstanding rib 56 on the frame base 2 and have their forward ends arranged in the paths of the bell crank levers 52, so that when the bell crank levers are released by the key levers, they abut the ends of the screws and are stopped thereby. By arranging the screws with their forward ends different distances from the plane of the rear edges of the bell crank levers 52 when the latter are in normal position, the differential movement of the levers 52 is provided and the consequent differential movement of the tape forwarding roller effected.

To better disclose the invention, I will describe the operation for making a record on the tape:

Assuming that it is desired to prepare the tape for sending the word "the." The key lever for the letter "t" is depressed. This movement rocks the rear end of said key

lever upwardly, causing the die 17 to punch through the tape 22 and leave therein a single aperture of two units length corresponding to the telegraphic dash. The depression of the key lever causes said lever to engage the universal bar 73, rocking the lever 70, throwing the detent tooth 70' into engagement with the ratchet wheel 46 to hold said wheel against the force of the spring motor, drawing back the arc-shaped bracket 62 through the linkage that connects it with the universal lever 70. Forward movement of the bracket 62 effects release of the pawl 59 from the ratchet wheel, so that the pawl and its lever 59' are free to move independently of the ratchet wheel. Following the release of the pawl 59 as described, the bell crank lever 52 for the "t" key lever is released by movement of the hook end of the key lever away from the hook end of the bell crank lever, and the bell crank lever is immediately drawn to the rear by its spring 54, such rearward movement continuing until the bell crank lever is stopped by abutment of its rear edge 90 against the end of its adjustable stop 58. Rearward movement of the bell crank lever 52 lifts the pawl lever 49 a distance corresponding to the rearward movement of the bell crank lever and the pawl is held in such advanced position and out of contact with the ratchet wheel until the key lever is released. With the teeth on the ratchet wheel arranged to represent units corresponding to the units of the character dies, the pawl will have been advanced to such a point that, when released, it will engage the fifth tooth back of the one against which it was seated prior to the operation just described, the five units representing the two units of the character and the standard three-unit space between characters. With the parts so set by and as a result of the depression of the key lever, when the lever is released, the detent 70' moves away from the ratchet wheel and the arc-shaped bracket 62 moves backwardly away from the pawl 59. The pawl, upon being released, moves into engagement with the ratchet wheel before the latter is released by the detent, so that movement of the ratchet wheel is immediately imparted to the pawl and its carrying lever. Release by the detent permits the ratchet wheel to advance under tension of the spring motor. This advance is imparted to the pawl 59 and thereby to the lever 49 and the universal rod 51 and from the rod 51 to the active bell crank lever 52, forcing the bell crank lever forward to its locking engagement with its key lever 14. Forward movement of the universal rod 51, the lever 49, the ratchet wheel 46, the spring motor and the tape forwarding roller is interrupted when the universal rod engages the inactive bell crank levers 52.

The key lever for the letter "h" is then depressed and the operation just described repeated, except that the distance moved by the parts differs from that of the previous 5 operation in that the movement is to the extent of ten units instead of five, as for the "t" character, the "h" character consisting of four dots of one unit value each, three spaces of one unit value each and a space 10 interval of three units. In order to provide the additional movement for a ten unit advance of the tape, the screw 58 for stopping the bell crank lever released by the "h" key lever is set back five units distance more 15 than that of the "t" character screw, so that the bell crank lever for the "h" character moves upwardly a distance three units greater than that for the "t" character. It is apparent that this additional movement 20 of the "h" bell crank lever induces a correspondingly additional movement of the pawl 59 so that the pawl reengages the ratchet wheel at a point ten teeth back of its original point of engagement instead of five 25 teeth back, as for the letter "t." It is further apparent that by reason of the greater rearward travel of the pawl advance of the ratchet wheel will be respectively greater than the advance for the letter "t" 30 and the record tape will have a corresponding advance.

When the key lever for the letter "e" is depressed, the operation is repeated and is identical with those just described, except 35 that the advance is for four units instead of five for the "t" character and ten for the "h" character, the "e" character comprising but a single dot, which, with the three unit interval between characters, requires a four 40 unit advance of the record tape.

It is apparent, therefore, that with a machine embodying my invention, the tape may be punched for characters of various lengths and advanced differentially to maintain 45 the proper spacing between characters, irrespective of the character lengths, thereby forming a record from which a message may be sent according to ordinary and standard practice.

It is also apparent that as the spaces between characters are standard and the difference in spacing dependent on the length of the characters, the space distance may be considered the base of the movement and 55 the character distance an increment over such base, the increment varying according to the length of the character.

The exact form of the perforating mechanism is not material in this application since 60 the specific perforating mechanism shown herein forms the subject matter of a separate application. Therefore, those claims in the present application which refer to perforating mechanism are intended to do so 65 only in a generic sense and irrespective of

whether an actual perforation is made or whether the tape is simply die pressed to provide an irregular surface or otherwise characterized.

Having thus described my invention what 70 I claim as new therein, and desire to secure by Letters-Patent, is:

1. In combination with separately operable members each comprising an individual portion for characterizing a record member, 75 means for advancing said member and a differential escapement selectively controllable by the characterizing members and limiting operation of the advancing means to a degree corresponding to the length of individual characterizations of the record member.

2. In combination with means for characterizing a record member comprising separately operable members each bearing individual indicia, the indicia of different members being of different length, means advancing said record member between characterizing operations, and means selectable by the characterizing members limiting operation of the advancing means proportionately to length of indicia on operated characterizing members.

3. In combination with members comprising indicia of different lengths, movable individually to characterize a record member, means advancing the record member between operations of the characterizing members to effect successive arrangement of the indicia in the record, and means controllable by the 100 characterizing members, selectively determining the advance of the record member according to length of indicia on corresponding characterizing members.

4. In combination with individually operable characterizing members, bearing indicia of telegraphic characters and movable to apply the indicia to a record member, means for advancing the record member, and an escapement comprising a member 110 individually controllable by each characterizing member, co-operating with the record advancing means to limit travel of the record member according to length of the indicia on the corresponding characterizing 115 member.

5. In combination with individual means for applying indicia of different lengths to a record member, single means for forward- 120 ing said record member following the application of the indicia thereto, and controlling devices individual to corresponding indicia applying means, co-operative therewith and with the forwarding means to limit movement of the record member proportionately to the length of relative indicia.

6. In combination with individually operable means for applying indicia of different length to a record member, means for for- 125 warding said member, and a differential es- 130

capement comprising members individually controlled by corresponding indicia applying means and a universal member operable by any individually controlled member and 5 coöperating with the forwarding means to limit advance of said means proportionately to the length of the indicia corresponding to the operated member.

7. In combination with individually operable members for applying indicia of different length to a record member, an escapement comprising members under control of corresponding indicia applying members, and means for limiting movement of said 10 controlled members proportionately to the length of corresponding indicia, mechanism for forwarding the record member, and universal mechanism settable by the controlled members and operable to limit movement 15 of the forwarding mechanism.

8. In combination with a member bearing indicia applicable to a record member to characterize said member, an escapement comprising a member under control of the 20 characterizing member and movable upon operation thereof, means limiting movement of the escapement member proportionately to length of the indicia on the characterizing member, and means, controlled by the 25 escapement, for advancing the record member.

9. In combination with characterizing mechanisms, comprising devices individual to each of a plurality of characters and including indicia of said characters for application to a record member, an escapement, escapement controlling members each individual to and under control of a relative characterizing device, means limiting movement of each escapement controlling member to a distance individual to its characterizing device, and means, controlled by any escapement controlling member, for forwarding the record member distances proportional to movements of the escapement 30 controlling members.

10. In combination with characterizing mechanism comprising a device including indicia of a character for application to a record member, an escapement member, yieldingly urged to a set position and normally restrained by said characterizing member, adjustable means limiting movement of the escapement member, and means, controlled by the escapement member, for advancing the record member proportionately to movement of the escapement member.

11. In combination with a key lever including indicia of a designated character, operable to impress a record member with such indicia, an escapement member normally latched by the key lever and yieldingly urged to assume set position when released by the lever, means limiting travel of

the escapement member at set position, and means, controlled by the escapement member, to advance the record member a distance proportional to movement of the escapement member.

12. In combination with a key lever, comprising a character die and latch hook, an escapement comprising a freely movable member, having a latch hook normally engaged by the lever hook, means yieldingly urging the escapement member to set position, an adjustable stop for the escapement member, and means, under control of the escapement member, for advancing a record member.

13. In combination with means for perforating a tape, means for advancing the tape between perforating operations, an escapement controlling the advancing means, and means for adjusting the escapement to vary the space between perforations effected at different operation of the perforating means.

14. In combination with a digitally operated die member, a complementary die member, and means for feeding a tape between the die members at varying increments of movement, the feeding means being controlled by the digitally operated die member.

15. A driving member, a driven member, an escapement for the driven member comprising a ratchet fixed to the driven member, an unconfined ratchet-engaging pawl movable about the ratchet, variable throw devices for operating said pawl and independent key releasing means for each throw device.

16. An escapement for driven members comprising an engageable member, an engaging member, variable throw devices for actuating the engaging member, digitally operated releasing means for the throw devices, and means for releasing the engaging device from the engaged device.

17. An escapement for a driven member comprising an engaging member fast on the driven member, an unconfined engaging device to engage the engaged device, variable throw latches to move the engaging device into engaging position with the engaged device, and digitally operated means for releasing said latches.

18. The combination with a die member having a plurality of die receiving openings, digitally operated die members arranged in banks and having dies receivable in selected openings in the first named die member, a tape movable between the complementary die members, means for feeding said tape comprising a rotatable shaft, and means responsive to a particular digitally operated die member for controlling the extent of movement of the shaft.

19. The combination with a driven member, of an escapement therewith comprising

a ratchet on the driven member, an unconfined pawl for engaging said ratchet, a frame upon which the ratchet is mounted, a plurality of latch levers having varying 5 throws and adapted to independently engage the frame to effect variation in the throw of the pawl, a detent coöperating with the pawl, key levers normally holding the

latch levers inoperative by effecting to release them by manual application, and means 10 for simultaneously releasing the pawl from the ratchet and moving the detent into engagement therewith.

In testimony whereof I affix my signature.

EDWIN H. PIERSEN.
